CARTON STENCILING DEVICE

Seth L. Winslow, Parlin, N. J., assignor to E. I. du Pont de Nemours & Company, Wilmington, Del., a corporation of Delaware

Application July 11, 1936, Serial No. 98,186

4 Claims. (Cl. 101—123)

This invention relates to a stenciling machine and more particularly to one of the automatic type for use in stenciling shipping cartons and the like.

At the present time, due to the cheapness of corrugated paper cartons and their combination of light weight and strength, a great many are used in shipping small and medium-sized packages. It is usually necessary to letter each carton with the name of the addressee as well as miscellaneous information such as contents, lot number, etc. This is usually done by means of a stencil which may be made of any thin, strong material such as paper, brass and the like. The stencil is held in place with one hand and the inked brush is applied with the other. There are also stenciling devices consisting essentially of a roll which holds type. The type of the roll is inked continuously as the carton passes under the roll so that the legend is applied to the moving carton. Equipment of this type is fairly satisfactory for marking lot numbers or dates, but is not particularly satisfactory for printing long names and addresses. Such equipment is not adapted for stenciling the ends of a carton. This is important because advertising and trade-marks are usually printed on the top and sides, but information peculiar to the individual carton should be printed on the ends since these are the only surfaces which can normally be seen when the cartons are stored or placed in a pile. For this reason, it is highly important to have a mechanical device for stenciling the ends of cartons.

The hand method is unsatisfactory where a large number of cartons are to be stenciled due primarily to the time and expense involved. Furthermore, it is also difficult to obtain clear, neat stenciling work by hand. The reason for this is that the stencil is usually made of thin material and must be held firmly at the area at which the ink is applied. When the hand is moved from one place to another, the stencil often slips and the work may be blurred or unreadable. If the stencil is held crooked, the legend makes a very poor appearance. These facts, coupled with the time involved for stenciling by hand, present an urgent need for equipment which produces stenciling which is neat and which may be done quickly. An object of the present invention is the provision of a machine for stenciling cartons which is entirely automatic for cartons of the same size and which does not require a workman for its operation except to apply more ink occasionally.

A further object of the invention is the provision of a machine which stencils cartons neatly and quickly with printing or a design of any reasonable size. Other objects will appear hereinafter as the description proceeds.

These objects are accomplished by a machine having a belt conveyor which delivers the carton through adjustable side guard rails which are adapted to hold the carton firmly in position while the stenciling is being applied. The stencil and brush are mounted in a frame which swings about a vertical shaft. As the frame swings against the end of the carton, the brush automatically moves across and back over the face of the stencil thereby printing the legend on the end of the carton. The carton is then released and passed over the conveyor for storage or shipment.

In the drawings, Figure 1 represents a side elevation, Figure 2 is a front elevation, and Figure 3 is a top plan view of the safety switch. Figure 4 is an elevation of the same switch. Figure 5 is a diagrammatic iso-metric arrangement of the parts. Figure 6 is a detailed view of the device for holding the carton in place and means for releasing it after it is printed. Figure 7 is a detailed view of the stencil holder. Figure 8 is a detailed elevation of the stencil holder.

In all the figures, 1 represents rolls which make up the roller conveyor for carrying the carton to the printing device. A belt 2 passes over the rolls 1 to assist in carrying the carton into and away from its position as it is stenciled. A tripping lever is indicated as 3 which extends slightly above the plane of the conveyor and which in turn operates a clutch 4. Guides which hold the carton in position and which are adjustable are indicated as 5. A stop is shown as 6 which prevents the carton being stenciled from passing too far on the conveyor belt. The frame which holds the stencil is shown as 7 and mounted thereon is the stencil 8 and the brush 9. The brush is moved across the stencil by the rod 10 and lever 11 which is mounted on the shaft 12 which in turn revolves in the hollow shaft 13. This is operated by the friction clutch 14. This in turn is operated by the shaft 15, lever 16, rod 17, and lever 18. The latter is mounted on the shaft 19 which is operated through gears 20 and 21. Mounted on the same shaft 19 is a disc 22 having a cam 23 mounted on its face. As the disc revolves, it raises the lever 24 against the tension of the spring 25 which in turn through levers 26 and 27 drops the stop 6.

Also, mounted on the shaft 19 is a segment 28

of a disc 28 which bears against the guides 5 to assist in holding the carton in position while it is being printed. The mechanism is operated by the motor 29, gear box 30, chain and sprockets 31, 32, 33, 34, 35, and 36.

In the operation of the machine, the carton is delivered to the stenciling device by means of the rollers and belts 1 and 2. When the carton passes over the tripping lever 3, the machine is set into motion through levers, which engage the positive type clutch 4 which allows the mechanism to go through one complete cycle of operation. As shown in Figure 2, the clutch 4 is activated through levers by a carton passing over the trip 3. The clutch 4 is of the one revolution type similar to those used on a punch press. When the tripping lever 3 is depressed by the carton, clutch 4 is operated through levers so that it engages the load and pulls it through 360°, after which it disengages itself and remains at rest until tripped again. The carton then moves to stop 6 and the guides 5 are pressed firmly against the carton by means of the segmental disc 28. When the trip lever 3 has been actuated, the carton travels promptly up to stop 6. The frame 7 then swings through 90° about the shaft 12 when a spring latch on the outside end which is beveled in the front side snaps into a rectangular socket to hold the frame during the stenciling operation. The shaft 12 turns the frame 7 by a connection through the friction clutch 14 which is in turn connected to the hollow shaft 13. This hollow shaft is connected rigidly to the frame 7 and when the frame reaches the end of its travel in position across the end of the carton, the friction clutch 14 slips leaving the hollow shaft 13 stationary but the inside shaft 12 continues to turn and slides the stencil brush 9 which is in turn operated by the rod and levers 10 and 11 completely across the stencil 8 and back to the normal position as shown in Figure 7.

As the brush returns to the normal position it comes in contact with the vertical piece 39 on the spring latch (Figure 8) mentioned above and pulls this latch out of the socket. The frame 7 is then free to swing 90° from the end of this carton to the open position. The stop 6 is then pulled down by levers 24, 26, and 27 and the action of the cam 23. The belt 2 then pushes the carton forward out of the machine and the stop 6 is returned to its original position by the spring 25. The machine is then again in position to receive the next carton. The segmental disc 28 is also designed so that it revolves with the shaft 19 and comes in contact with the guide rails 5 pressing the same slightly against the side of the carton to hold it firmly during the stenciling operation. This disc turns and leaves the guide rails free which allows the cartons to enter and leave the machine.

The brush 9 is held in the frame 7 by a bolt and wing nut. This frame is slotted so that the brush can be adjusted vertically for the desired position for stenciling. The stencil is held in the frame 7 by a vertical clamp on the outside of the frame. A small metal hook is clamped on to the other end of the stencil and hooked around a vertical spring. The stencil can be set at any height in the frame 7. The brush is also easily replaceable and one is selected for the proper width of the stencil. These brushes have a soft felt pad in the center with bristles on either side. The felt pad extends to the end of the bristles and is kept moist with ink as needed.

75 The safety switch arrangement is located on

the bottom of the frame 7 as shown in Figures 3 and 4 which consists of a lever 37 attached to an electrical switch 38. As the frame 7 moves through 90° parallel to the end of the carton if any obstruction comes in contact with the lever 37, which is very easily moved, the switch 38 is opened and the machine is stopped thereby avoiding damage or errors in operation. The lever 37 is held in an outward position by a spring not shown. After the frame 7 reaches its final position in this travel, the lever 37 is moved but at this time the switch 38 is mechanically held in contact for the continuous operation for one cycle of the machine.

As the frame 7 swings 90° around shaft 12 the safety switch lever is carried with it in the position shown in Fig. 3. During the movement of the frame if any obstruction comes in contact with lever 37, it is easily moved and operates electrical switch 38 and stops the machine. When frame 7 finally comes into place over the end of the carton the lever 37 is moved back in line with frame 7 and would normally open the switch 38 and stop the machine. However, there is a spring connection in the linkage to allow the lever 37 to make this movement while at this location the switch 38 is mechanically stopped from opening and stopping the machine. As soon as the frame 7 moves away from the face of the carton the switch 38 and lever 37 are again operative to stop the machine. The switch 38 is normally closed so that the machine will operate.

The machine herein described is of particular value for stenciling on the end of paper shipping cartons and the like with the name of the product, date, serial number, or other manufacturing information. It may also be used for printing any design, trade mark, or other legend. The machine herein disclosed is preferably a double unit with two stenciling devices, one for each of two package lines, and so arranged that the stenciling is alternate; that is, one side and then the other, but not stenciling both sides at the same time although this may be done if desired. The preferred method of operation avoids any possible jamming of the cartons when released because both production lines are delivered to the same conveyor. When a single production line is fitted with the machine herein described, the double arrangement would not be necessary.

The machine herein disclosed offers several advantages over hand stenciling as indicated above. It is also designed to use paper stencils because of their relative cheapness, although any suitable material such as copper, bronze, or silk may be used. In addition to being cheap, paper stencils are quickly and easily cut and are in general preferred.

It is apparent that many widely different embodiments of this invention may be made without departing from the spirit and scope thereof; and, therefore, it is not intended to be limited except as indicated in the appended claims.

I claim:

1. An automatic stenciling device comprising a conveyor belt for conveying the carton to be stenciled into position, guide rails, means for pressing the guide rails against the carton, a rotatable stencil holder mounted on a vertical shaft, means for rotating the said stencil against the end of a carton and mechanical means for moving a brush across the face of the stencil whereby a legend is stenciled on the carton.

2. An automatic stenciling device for stenciling cartons comprising means for moving a carton up

to and away from a predetermined position, means for holding the carton firmly in the said position while it is being stenciled, and a rotatable stencil holder mounted on a vertical shaft, 5 mechanical means for moving a brush across the face of the stencil whereby a legend is stenciled on the carton, means for swinging the stencil holder away from the carton, and means for releasing the carton from the said pre-determined 10 position.

3. An automatic stenciling device comprising a conveyor adapted to move a carton to and from a pre-determined position, adjustable guide rails at the said position for holding the carton firmly, 15 and means for pressing the said guide rails against the sides of the carton, a stencil holder adapted to swing against the carton, and a brush adapted to be moved across a stencil while the said stencil holder is against the carton, means 20 for removing the stencil holder from the path of

the carton, a stop adapted to be interposed temporarily in the path of the carton, and means for removing the stop from the said path.

4. An automatic stenciling device comprising a conveyor adapted to move a carton to and from 5 a pre-determined position, a tripping device in the path of the said carton before it reaches the said pre-determined position, said tripping device adapted to set the stenciling device in operation for one complete cycle only, adjustable guide rails 10 disposed on each side of the carton, means for applying temporary pressure against the sides of the carton, a stencil holder, a stencil mounted therein, and a brush adapted to be moved across the face of the stencil, means for swinging the 15 said stencil holder against the end of the carton, and means for actuating the said brush while the holder is in this position.

SETH L. WINSLOW. 20
